UNITED STATES PATENT OFFICE.

THOMAS J. MAYALL, OF BOSTON, MASSACHUSETTS.

DESIGN FOR A GAS-HEATER.

Specification forming part of Design No. 5,811, dated April 23, 1872.

SPECIFICATION.

To whom it may concern:

Be it known that I, THOMAS J. MAYALL, of Boston, Suffolk county, Massachusetts, have invented a new and original Design for a Gas-Heater or Stove, of which the following is a specification:

In the accompanying drawing, Figure 1 is a top view of the heater. Fig. 2 is an elevation of the same.

A is the top plate, made of cast metal, molded in the open-work pattern represented in Fig. 1, an opening of proper size being left in its center part corresponding in size to the top of the gauze-covered heating-chamber B, into which the gas is introduced through pipe a. The top plate is supported on legs C, having the configuration substantially as shown in Fig. 2, each with the representation of an

animal's head at the top and a paw at the bottom. The gas-chamber B, which is supported on a plate, b, attached to the legs C, has the configuration shown in Fig. 2.

What I claim, and desire to secure by Letters Patent, is—

1. The design for the top plate of a gas-heater or stove, substantially as shown in Fig. 1 of the accompanying drawing.
2. The design for the legs of a gas-heater or stove, as shown in Fig. 2 of the accompanying drawing.
3. The design for a gas-heater or stove as a whole, as herein shown and described.

THOS. J. MAYALL.
